US0D1038225S

(12) **United States Design Patent** (10) Patent No.: **US D1,038,225 S**
(45) Date of Patent: ** Aug. 6, 2024

(54) **PAYMENT TERMINAL WITH SCREEN AND KEYBOARD**

(71) Applicant: **BANKS AND ACQUIRERS INTERNATIONAL HOLDING, Suresnes (FR)**

(72) Inventor: **Fabien Demange, Fontenay-sous-Bois (FR)**

(**) Term: **15 Years**

(21) Appl. No.: **35/517,738**

(22) Filed: **May 16, 2023**

(80) **Hague Agreement Data**

Int. Filing Date: **May 16, 2023**

Int. Reg. No.: **DM/230006**

Int. Reg. Date: **May 16, 2023**

Int. Reg. Pub. Date: **Jul. 7, 2023**

(51) **LOC (14) Cl. 18-01**

(52) **U.S. Cl.**

USPC **D18/4.6**

(58) **Field of Classification Search**

Primary Examiner — Marie D. Fast Horse

(57) **CLAIM**

The ornamental design for a payment terminal with screen and keypad, as shown and described.

DESCRIPTION

1. Payment terminal with screen and keyboard

1.1: Front

1.2: Back

1.3: Top

1.4: Bottom

1.5: Right

1.6: Left

1.7: Perspective

1.8: Perspective

Payment terminal with screen and keyboard.

The broken lines in the drawings depict portions of the Payment terminal with screen and keyboard that form no part of the claimed design.

1 Claim, 8 Drawing Sheets
